D. A. CUMFER

SHINGLE STRIP AND METHOD OF MAKING IT

Filed Sept. 17, 1920

Inventor:

Donald A. Cumfer

By Foxie Bain Hiniker
Atk's.

UNITED STATES PATENT OFFICE.

DONALD A. CUMFER, OF DETROIT, MICHIGAN.

SHINGLE STRIP AND METHOD OF MAKING IT.

Application filed September 17, 1920. Serial No. 410,841.

To all whom it may concern:

Be it known that I, DONALD A. CUMFER, a citizen of the United States, residing at Detroit, in the county of Wayne and State 5 of Michigan, have invented certain new and useful Improvements in Shingle Strips and Methods of Making Them, of which the following is a specification.

The invention relates to improvements in 10 shingle strips and a method of making them.

The objects of the invention are to improve the appearance, decrease the cost of construction and make a more durable and efficient shingle simulating strip.

15 The invention is especially concerned with asphalt roofing into which a paper or felt base may have an overlying layer of asphalt deposited thereon with an outer coating of slate or other mineral substance adhering to the asphalt to give it color, characteristic of the mineral coating. Roofing of this general character is made in long continuous sheets and thereafter notched and cut into strips which, when properly 20 laid on the roof present the appearance of separated shingles. Each strip is notched transversely, at intervals, to give the appearance of separated shingles, at the notched ends. When the strips are laid 25 upon a roof the notches of one course are placed midway between the notches of the adjacent courses and thus only the parts of the strips between the bounding notches are visible to the eye of the observer.

30 The separated tabs, of such strips, are more liable to be lifted by wind and rain than would be the case if the strips were not divided into a plurality of tabs or shingle adhering parts or if the notches 35 did not extend entirely thru the strip structure. Except for appearances the strip would make a better roof if they were not so transversely notched.

35 In carrying my invention into effect, I depress selected areas of the mineral into and below the asphalt layer which overlies the sheet of felt, so that in these selected areas the color of the asphalt shows clearly thru the slate or other finely divided mineral matter, the slate being thus submerged in the asphalt, the black color will show in contrast to the overlying coating of mineral, and the black color thus produced being about as wide and long as the usual slot 40 made in the shingle strip, will have the appearance of complete separation as the usual separate shingles, when laid upon the roof. This produces a very superior article 45 because the strip remains in a single piece unslotted, thereby being stronger and less liable to curl up by the effect of the sun or by the effect of wind and storm when placed upon the roof.

In Figs. 1 and 3 of the drawings I have shown a schematic arrangement of apparatus by which the invention may be carried into effect.

Figs. 2 and 4 show the manner in which the sheet may be divided into a plurality of strips. In Fig. 2 the strips are cut from 50 the sheet lengthwise of the strips and the sheet is divided longitudinally into a number of long strips, from which the shingle strips are severed. In Fig. 4 the strips are cut the length of the shingle in width and 55 transversely of the sheet.

Fig. 5 is a section of the strips thru lines 5—5 of Fig. 4 and thru lines 5—5 of Fig. 2, showing the depressed area or kerfs.

The sheet of roofing material 10, made in 60 the manner heretofore described, passes over the folder or take up 11, as usual. It then takes a path between the rollers 12 and 13 and under a roller 14 and finally over the roller 15. It then passes between the rollers 65 16 and 17, the former having four depressing extensions 18 extending radially from the circumferential surface of the roller 16. The distance that the extensions 18 are apart is substantially equal to the distances 70 between two adjacent depressed areas or kerfs 19 made in the shingle simulating strip 20. 21 is the sheet of felt forming the base for the sheet of roofing material and 22 is the overlying layer of asphalt. 23 is 75 the overlying covering of granular, or otherwise divided mineral, such as slate and the like, which gives color to the roofing strips. 24 and 25 are slitting knives which slit 80 the sheet on the line 25 of Fig. 2, while the rotating guillotine knife 26 cuts the sheet shown in Fig. 2, transversely on the line 27. The rollers 28 and 29 represent the conventional feed rollers by which the strip 85 is drawn thru the machine. Looking at Fig. 5 it will be noticed that the depressions 19 are made below the surface 23 and into the surface 22. When the slate is pressed down into the body of the asphalt layer 22, 90 the asphalt will rise up and completely cover the area of slate to which the pressure is applied, therefore making the kerfs 19 black,

2
or the color of the asphalt, which when viewed, after the strips have been placed upon the roof, will look as much like a separation between adjacent tabs of the strips as if the strips were notched or cut through as usual. The projections 18 extend in a direction parallel with the axis of the roll 16 while the projections 18' of Fig. 3 extend circumferentially of the roll 16'. That is because the strip 10 is divided somewhat differently in the two examples. The rolls 16-16' may be either cold or hot but usually better results are produced when the rolls are hot, especially is this true when the strip 10 has been cooled after the coatings 22 and 23 have been applied thereto.

The sheet 10 is kept constantly moving until the simulating strips have been made and severed from the sheet. The sinking of the projections 18-18' into the asphalt serves as means to assist the feed rollers 28 and 29 in pulling the sheet thru the machine.

The movement of the sheet is timed with respect to the knife 26, so that one revolution of the knife will sever the sheet in proper lengths, in making the strips shown in Fig. 2, or, in Fig. 4, the relative movement of the knife being somewhat different in the two arrangements. It will be manifest, of course, that the depressions 19 are uniformly separated so that the tabs will

be of uniform width and the shingle strips of proper length.

Having described my invention what I claim as new and desire to secure by Letters Patent is:—

The method of making shingle simulating strips which consists in providing an elongated sheet of roofing material comprising a base sheet having a coating of plastic asphalt of uniform thickness and a covering of finely divided mineral substance of contrasting color; continuously moving the sheet, and while moving embedding a group narrow relatively long spaced, parallel straight areas of said mineral substance at separated regular intervals into the subjacent plastic coating until the latter shows on the face of the sheet in simulation of separate shingles, then severing the sheet into shingle strips by cutting it on a line in a plane with like terminal ends of said groups of areas, with the areas extending from a common edge of the severed strips to the transverse mid-portion thereof, leaving substantially one-half of the strips, extending longitudinally thereof, unprovided with the depressed areas.

In testimony whereof I hereunto subscribed my name.

DONALD A. CUMFER.
